[57] ABSTRACT

A folding table consisting of a top board and a bottom shelf, with respective supporting leg assemblies hinged to opposite edges of the top board. One leg assembly has a cross bar to which one transverse edge of the bottom shelf is hinged, and the shelf has a resilient channel element on its other transverse edge lockingly receiving a cross bar on the other leg assembly. The channel element can be disengaged from its locking position and the shelf can be swung into an inverted overlying position covering the top board, with the leg assemblies swung to overlapping positions, closely received between the top board and the shelf. The top board is provided with various accessories foldable to positions close to the top board and covered by the shelf when the table is in its folded condition.

COLLAPSIBLE PORTABLE UTILITY TRAY STAND

This invention relates to folding tables or tray assemblies, and more particularly to a foldable table assembly particularly useful for picnics or other outdoor activities.

A main object of the invention is to provide a novel and improved folding table or tray stand which is relatively simple in construction, which is easy to set up for use, and which is foldable to a very compact unit so that it can be easily transported or stored.

A further object of the invention is to provide an improved foldable table or tray stand which is inexpensive to manufacture, which is durable in construction, and which is especially useful for outdoor activities, such as for picnics, camping, or general recreational activities.

A still further object of the invention is to provide an improved folding table or tray stand which can be conveniently carried to a chosen location and set up for use in a very short time and with a minimum amount of effort and which includes a number of useful accessory items of particular value for outdoor activities, such as an arrangement for holding beverage containers, cigarettes, magazines, newspapers, or other items.

A still further object of the invention is to provide an improved foldable portable tray stand or table for recreational use or for any other purpose, the device being easily transportable from one location to another, being capable of being set up without requiring the use of any tools, and being adapted to be set up or folded by relatively simple manipulations.

Further objects and advantages of the invention will become apparent from the following description and claims, and from the accompanying drawings, wherein:

FIG. 1 is a perspective view of an improved foldable table or tray stand constructed in accordance with the present invention, shown set up for use.

FIG. 2 is a vertical cross-sectional view taken substantially on the line 2—2 of FIG. 1.

FIG. 3 is a perspective view of one of the supporting leg assemblies employed in the foldable table or tray stand shown in FIG. 1.

FIG. 4 is an enlarged perspective view showing the ash tray employed on the top board of the tray stand of FIG. 1 and illustrating the manner of detachably securing the ash tray to said top board.

FIG. 5 is a fragmentary horizontal cross-sectional view taken substantially on the line 5—5 of FIG. 2.

FIG. 6 is a vertical cross-sectional view taken substantially on the line 6—6 of FIG. 5.

FIG. 7 is an enlarged fragmentary horizontal cross-sectional view taken substantially on the line 7—7 of FIG. 1.

FIG. 8 is a vertical cross-sectional view taken substantially on the line 8—8 of FIG. 7.

FIG. 9 is a perspective view showing the tray stand or table of FIG. 1 in its fully folded condition.

FIG. 10 is a vertical cross-sectional view taken substantially on the line 10—10 of FIG. 9.

Referring to the drawings, 11 generally designates an improved folding table or tray stand constructed in accordance with the present invention. The folding stand or table 11 comprises a generally rectangular top board 12 which may be of any suitable size and which may be, for example, substantially square as illustrated. Obviously, the shape and dimensions of the board may be selected in accordance with the requirements of use of the device.

Top board 12 is integrally formed at opposite transverse edges thereof with generally cylindrical hinge sleeve elements 13 and 14 and is provided at its remaining edge portions with upstanding flanges 15 and 16.

5 The device is also provided with a bottom shelf 17 which is generally similar in shape to the top board 12 but is slightly narrower in transverse width and which is provided with upstanding front and rear marginal flanges 18 and 19. The upstanding flanges 18 and 19 are substantially greater in height than the upstanding flanges 15 and 16 of top board 12, the flanges 18 and 19 being inwardly offset relative to the top board flanges 15 and 16 for a purpose presently to be described.

15 The shelf member 17 is integrally formed at one transverse edge thereof with a generally cylindrical hinge sleeve 20 which rotatably receives the cross bar element 21 of a first supporting leg assembly 22, shown in FIG. 3. The leg assembly 22 is provided with upwardly convergent support rod elements 23, 23 and the rod elements 23 merge with the cross bar element 21 by the provision of end loops 24, 24 which integrally connect the ends of cross bar element 21 with the side rod elements 23, 23. The top ends of the rod elements 23, 23 are provided with outwardly offset aligned hinge pin elements 25, 25 which are connected integrally with the top ends of the rod elements 23, 23 by outwardly directed arm portions 26, 26, the hinge pin elements 25, 25 being upwardly offset relative to the plane defined by the arm elements 26, 26, as shown in FIG. 3.

20 The hinge pin elements 25, 25 rotatably engage in the opposite end portions of the hinge sleeve element 13 of top board 12. As shown in FIG. 1, clockwise rotation of the bottom shelf 17 relative to the base loops 24, 24 is limited by the provision of depending stop flange elements 31, 31 integrally provided on the transverse edge of shelf 17 adjacent the opposite ends of the hinge sleeve 20.

25 An additional supporting leg assembly 22' identical in shape to the supporting leg assembly 22 is provided at the opposite side of the device, the assembly 22' being provided with the aligned pivot pin portions 25', 25' which rotatably engage in the opposite ends of the hinge sleeve element 14.

The member 22' is provided with a cross bar element 21' which is lockingly received in a resilient hook-shaped channel 32 integrally formed on the transverse edge portion of shelf 17 opposite hinge sleeve 20. Shelf 17 is formed with upstanding

30 locking lugs 33, 33 engageable in rectangular notches 34, 34 defined adjacent the ends of the channel 32 and limiting rightward movement of the shelf 17, as viewed in FIG. 1, as the hook-shaped channel 32 is forced downwardly over the cross bar element 21', whereby

35 the channel 32 is caused to flex as it is pushed downwardly and to snap over the cross bar element 21' to lockingly engage therewith in the manner illustrated in FIG. 2. Lugs 33 have end outwardly projecting protrusions or abutment elements 33' to prevent side shifting of members 22'.

40 The channel 32 is provided at its midportion with a downwardly and outwardly inclined gripping lug 35 and is formed with a generally semicircular aperture 36 adjacent said gripping lug to facilitate manual disengagement of the channel member 32 from the cross bar element 21' when the table is to be folded up, as will be presently described. Thus, the channel 32 may be dis-

engaged from the cross bar element 21' by grasping the lug 35 and at the same time exerting downward thumb pressure on the cross bar element 21' through the aperture 36. With sufficient thumb pressure applied to the cross bar element 21', the channel 32 can be flexed outwardly to allow it to be disengaged from the cross bar element.

As shown in FIG. 2, when the table is set up for use, the opposite transverse marginal portions of top board 12 are supported on the horizontal shoulder elements 26 and 26' of the respective supporting leg assemblies 22 and 22'. The device for instance supported on the ground or any other subjacent supporting surface by its bottom ground-engaging loop elements 24 and 24', as shown in FIG. 2.

Top board 12 is provided with a number of accessory elements including a foldable cigarette package holder, designated generally at 40, an ash tray, designated generally at 41, and a foldable beverage container support, designated generally at 42.

As shown in FIGS. 7 and 8, the foldable cigarette package container 40 comprises a generally rectangular receptacle 43 having end pivot studs 44, 44 located adjacent the right hand bottom corners thereof, as viewed in FIGS. 7 and 8, and being pivotally engaged in upstanding parallel lugs 45, 45 formed integrally on the board 12. The receptacle 43 has an open end which faces upwardly, as shown at 47, when the receptacle is in its upright position, illustrated in full line view in FIG. 8. The receptacle may be folded in a clockwise direction, as shown in FIG. 8, to a horizontal position adjacent board 12, as shown in dotted line view in FIG. 8. The receptacle 43 is provided at its left side, as viewed in FIG. 8, with an integral resilient leaf 46 extending substantially parallel to the adjacent side of the receptacle and serving as a retainer for a matchbook, or the like. Thus, the matchbook may be inserted between the resilient leaf 46 and the adjacent side of the receptacle 43 and may be thus resiliently clamped therebetween. When the table 11 is to be folded up for transportation or storage, the receptacle 43 is rotated to its dotted view position, shown in FIG. 8, so that it is disposed adjacent the board 12.

The ash tray 41 comprises a rectangular box 50 having opposite end walls 51, 51 formed with upstanding serrations 52 therebetween adapted to receive smoldering cigarettes. The spacing between the intermediate pairs of serrations 52 is preferably made somewhat larger than the other spacings to define wider V grooves 54 of sufficient size to receive smoldering cigars. The box-like receptacle 50 is adapted to be clampingly received between a pair of upstanding resilient lugs 56, 56 integrally formed on board 12, the lugs having opposing convex inwardly projecting detent portions 58, 58 which are lockingly engageable in notches 59, 59 formed in respective front and rear walls 60' and 61' of the box-like member 50. Thus, the box-like member 50 is normally gripped between the lugs 56, 56, with the detent elements 58, 58 engaging in the notches 59, 59. The box-like member 50 may be readily moved, however, by grasping the end walls 51, 51 and manually lifting the box-like member upwardly. Thus, the box-like member 50 may be disengaged from the lugs 56, 56 for emptying, as required, and can then be re-engaged between said lugs for further use.

The cigarette package receiving and supporting assembly 40 and the ash tray 41 may be located at diagonally opposite corner portions of the top board 12. The beverage container receiving and supporting assembly 42 may be located substantially centrally on the top board 12, as illustrated in FIG. 1. The assembly 42 comprises a main supporting rod 60 pivoted in a generally U-shaped upstanding lug 61 integrally formed on top board 12, the rod 60 having an integral bottom eye 62 rotatably engaged on a transverse pivot pin 63 secured between the side walls of the upstanding U-shaped lug 61. The transverse end wall 64 of said upstanding lug serves as a stop element to limit counterclockwise rotation of rod 60 and to thereby support the rod in its upstanding vertical position, as viewed in FIG. 6. The top portions of the side walls of the U-shaped member 61 are provided with inwardly projecting detent elements 65 located near the top ends of the side walls, the transverse wall 64 being notched at 66, whereby the top portions of the side walls of the U-shaped member are somewhat resilient. The detent elements 65 are therefore located so as to cooperate with the transverse wall 64 to retain the rod 60 in its upright vertical position, shown in FIG. 6, but the upper portions of the side walls of the U-shaped member 61 are sufficiently resilient to allow the rod 60 to be rotated in a clockwise direction, as viewed in FIG. 6, to a position substantially parallel to the table board 12, as shown in FIG. 10. The rod 60 is formed at its top end with a horizontally elongated grasping ring 67 for manipulating the rod 60.

The upstanding U-shaped member 61 has parallel right end wall portions 69, 69 which are offset inwardly relative to the main side wall portions of member 61 and which are reduced substantially in height relative thereto, as shown in FIG. 6. Designated at 70, 70 are respective generally circular beverage container-supporting rings which have parallel end arms 71, 71. The arms 71, 71 extend substantially tangentially relative to the circular ring portions of the members 70, 70 and are pivotally connected at 73, 74, respectively, to the intermediate portion of rod 60 and a link arm 75. The lower portion of arm 75 is received between the reduced wall elements 69, 69 and is pivotally connected therebetween at 76. Thus, as shown in FIG. 6, the members 70, 70 extend on opposite sides of the vertical plane defined by rod 60 and link bar 75 and form part of a parallelogram linkage, since rod 60 extends parallel to link arm 75 and the tangential arm elements 71, 71 extend parallel to table board 12. Thus, in the upstanding vertical position of rod 60, the ring members 70, 70 are substantially horizontal and are elevated, as shown in FIG. 6. By rotating the rod 60 in a clockwise direction from the position thereof shown in full line view in FIG. 2 to the substantially horizontal position thereof, the ring elements 70, 70 may be lowered to positions below the level of the top edges of the higher portions of the side walls of the upstanding lug member 61, as shown in FIG. 10.

The bottom shelf member 17 is provided with an upstanding integral headed lug element 80 which is lockingly engageable between the resilient top portions of the side walls of the generally U-shaped lug member 61, the lug 80 having an enlarged head portion 82 which is lockingly receivable below the detent lug ele-

ments 65, 65. Thus, the shelf member 17 may be releasably locked in the position thereof shown in FIG. 10 by the interlocking engagement of the headed lug 80 with the detent lugs 65, 65.

To fold up the table for transportation or storage, the accessory elements carried on the top board 12 are first folded to their inoperative positions, namely, the cigarette package-receiving member 43 is folded to the dotted view position thereof shown in FIG. 8 and the beverage container-supporting assembly 42 is folded to its lowered position by rotating the rod member 60 clockwise, as viewed in FIG. 2, to bring said rod member substantially to the position thereof shown in FIG. 10. The channel member 32 is then disengaged from the cross rod element 21' in the manner above described and the supporting assembly 22' is then swung counterclockwise, as viewed in FIG. 1, to a position overlying and substantially parallel to the table top board 12. The supporting assembly 22 is then swung clockwise, as viewed in FIG. 1, to a position overlying the top board 12 and the bottom shelf member 17 is rotated counterclockwise to the position thereof shown in FIG. 10, wherein it is substantially parallel to and overlies the other elements of the assembly. In this position, the detent lug 80 can be forced into locking engagement with the somewhat resilient top portions of the side walls of the generally U-shaped upstanding lugs 61, as above described, thus locking the assembly in its folded position, with the parts disposed substantially in the manner illustrated in FIGS. 9 and 10.

To set up the device for use, the above-described procedure is reversed.

It will be seen from FIG. 9 that in the folded position of the device, the front and rear upstanding flanges 18 and 19 of the shelf member 17 are substantially in abutment with the top board 12 and are received inwardly of the upstanding flanges 15 and 16 of said top board. It will be further seen that the shelf member 17 is inverted as compared with its normal relationship relative to top board 12. It will be noted that the gripping ring member 67 projects from one edge of the folded table assembly 11, as shown in FIG. 9, so that this member 67 may be employed as a carrying handle for the folded assembly. Similarly, when the device is in its operating position, namely, the position shown in FIG. 1, the gripping element 67 may likewise be employed for bodily lifting the entire assembly and moving it to a desired location.

The top board 12 and the shelf member 17, as well as the other parts of the assembly, may be made of any suitable material, such as metal, molded plastic, or the like. Thus, in a typical embodiment illustrated in the drawings, the top board 12 and the shelf member 17 are shown as being made of suitable plastic material. Also, in the typical embodiment illustrated the cigarette package holder 40 and the ash tray 41 are likewise shown as being made of plastic material. The other parts are shown as being made of metal. However, the choice of materials is arbitrary and can be made in accordance with the judgment of the fabricator of the assembly.

The folding table and tray assembly above described is of great value as an accessory for beach goers since it can be advantageously employed for persons enjoying relaxation at the beach.

It is to be noted that areas adjacent the free corners of the top board 12 are available for use in supporting various objects such as snacks, sandwiches, or the like, and that these free areas can be employed for any other desired use.

While a specific embodiment of an improved foldable table or stand assembly has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A foldable table assembly comprising a top board member having parallel opposite edge portions, a first support hinged to one of said edge portions and having a lower first cross rod element parallel to said one end edge portion, a second support hinged to the other end edge portion and having a lower second cross rod element parallel to said other end edge portion, said supports being swingable to overlapping positions overlying said top board member, a shelf member hinged at one edge thereof to said first cross rod element, means on the shelf member adjacent the opposite end edge thereof lockingly engageable with said second cross rod element, said shelf member being swingable to an inverted position substantially parallel to said top board member when said second support is in a position overlying said top board member, upstanding lug means on the top board member, and a projection on said shelf member shaped to lockingly interengage with a portion of said lug means when the shelf member is in said inverted position.
2. The foldable table assembly of claim 1 and a handle rod element hingedly connected to said lug means.
3. The foldable table assembly of claim 1, and wherein said portion of the lug means is shaped to resiliently and lockingly receive said projection.
4. The foldable table assembly of claim 1, and wherein said supports are provided with inwardly extending shoulder elements adjacent their hinged connections, said shoulder elements being located so as to supportingly underlie said top board member when the supports are in depending operative position.
5. The foldable table assembly of claim 4, and wherein the means lockingly engageable with said second cross rod element comprises resilient channel means on said opposite end edge of the shelf member adapted to grippingly receive said second cross rod element.
6. The foldable table assembly of claim 5, and upstanding stop flange means on said opposite end edge of the shelf member adjacent said resilient channel means located to abut said second cross rod element and to grip said cross rod element in cooperation with said resilient channel means.
7. The foldable table assembly of claim 2, and a beverage container-supporting means arranged parallel to said top board member, and means interconnecting said beverage container-supporting means, handle rod element and top board member and defining a parallelogram linkage, whereby said beverage container supporting means may be raised and lowered relative to said top board member.

8. The foldable table assembly of claim 1, and a cigarette package supporting receptacle hingedly connected to said top board member and being swingable from a lowered position substantially parallel to said top board member to an upright position relative to 5 said top board member.
